UNITED STATES PATENT OFFICE.

DANIEL W. ROBERTS, OF WORCESTER, MASSACHUSETTS.

MEANS FOR ACTUATING WINDOW-BLINDS.

SPECIFICATION forming part of Letters Patent No. 699,850, dated May 13, 1902.

Application filed December 21, 1901. Serial No. 86,852. (No model.)

To all whom it may concern:

Be it known that I, DANIEL W. ROBERTS, a citizen of the United States, residing at Worcester, in the county of Worcester and 5 State of Massachusetts, have invented certain new and useful Improvements in Means for Actuating Window-Blinds, of which the following is a specification.

My invention relates to that class of sliding 10 window-blinds which may be swung outwardly to form an awning and movably mounted on an overhead track, upon which said blind may slide and swing outwardly, with actuating means for opening and closing 15 said blinds from the interior of the house.

The object of my invention is to provide 20 strong, simple, and efficient means for actuating and controlling window-blinds of the class referred to and not disengage said actuating mechanism whenever it is desired to swing blind outward.

To these ends my invention consists of the 25 parts and combination of parts, as hereinafter described, and more particularly pointed out in the claims at the end of this specification.

Window-blinds which are constructed according to my invention are movably mounted on an overhead track and are actuated by means of a simple mechanism consisting of 30 arms and jointed connections, with a spring-locking arrangement at the lower end of each of said blinds, means being provided for disengaging the said locking arrangement whenever it is desired to swing the blinds outwardly 35 to form an awning and to hold same in its relative position when not disengaged.

Referring to the drawings, Figure 1 is a rear elevation of a pair of blinds constructed according to my invention, the location of the 40 window-opening being indicated by dotted lines. Fig. 2 is an end view of Fig. 1 looking in direction of arrow A. Fig. 3 is an end view showing the blind in position to form an awning.

Referring to the drawings and in detail, A and B designate a pair of window-blinds having grooved rollers 1, which may move upon and turn about an overhead track 2'. Near its center and in the window-frame each of 45 the blinds A and B is provided with an actuating-shaft 3. These shafts being constructed of metal or any other substantial substance

are made to turn in said window-frame. I provide an actuating upward-extending arm D, (or, preferably, shaft 3 is bent to form said arm D,) which is secured to or fastened in a suitable manner to the actuating-shaft 3. The shaft 3 extends through to the inside of the house and is journaled in the window-framing in any suitable manner and is provided 60 at its inner end with a knob 5.

Each arm D is provided with a double-forked arm or swivel 6, one end of which will extend both sides of the arm D. The other end extends both sides of connector 7, fastened to arm D by pins or studs 8 and to connector 7 by stud 8.

Connector 7 is fast to a second fork-arm 9, which extends both sides of said connector 7, and is fast by stud 10 to said fork-arm, which 70 is pivoted to blind and allows connectors and blinds to move to position of blind A at the left of Fig. 1 and will insure the blind retaining its position as shown by position of blind B. Small coil-springs 11 are secured in stand 75 12, which are secured or held against blinds at inner ends. Said springs are fastened at one end of locking-wire E, which is journaled in stands 12 and 14 and locked to position by stand 15, thus holding blinds in their normal 80 and horizontal position, stands 12 14 being secured to each blind by screws or any other suitable manner.

It is obvious that when arms D are made to turn or move in either direction their natural tendency is to force the blind in same direction with said arms D or away from or toward shaft 3, thus bringing the rollers 1, which bear on overhead track, to move on said track, thus opening or closing said blinds.

When one of the blinds is in its closed position or opposite the window-opening, the outer end of arm E may be moved upwardly against the tension of the coiled spring 11 by means of the wire E', acting as a handle, thus 95 disengaging the part E' of the wire from the stand 15, leaving the blind free to be swung outwardly to form an awning or otherwise.

16 designates a suitable brace-rod, which may be pivoted to window-casing and may engage a suitable screw-eye 17 to hold the blind in its outward position, as described.

What I claim, and desire to secure by Letters Patent of the United States, is—

1. In a mechanism for actuating window-blinds movably mounted on an overhead track, upon which said blind may slide or be swung outwardly and form an awning the combination of said track, blind, actuating mechanism extending to the interior of the house connected with said blind to open and close said blind and allow blind to swing outwardly without disengaging from house or blind the said actuating mechanism, and a locking device secured to the said blind for normally holding blind in vertical position when not swung outwardly, capable of disengagement from a part secured on house to allow said blind to be swung outwardly as shown and described substantially.

2. The combination with actuating mechanism having a shaft extending into the interior of the house and actuating-arm having one or more connectors and swivels thereon and adapted to connect to a blind for open-

ing and closing said blind, of a blind having rollers adapted to turn about on an overhead track, an overhead track adapted to allow the blind to be swung outwardly to form an awning and on which it may slide to open or close the blind, and two-part locking device one part secured to the house, the other part secured to the said blind for normally holding blind in vertical position when not swung outwardly, capable of disengagement from part secured on house to allow the blind to be swung outwardly, substantially as shown and described.

In testimony whereof I have hereunto set 35 my hand in the presence of two subserbing witnesses.

DANIEL W. ROBERTS.
